Primary Examiner — Robin V Webster*(74) Attorney, Agent, or Firm* — Seed IP Law Group PLLC(57) **CLAIM**

The ornamental design for a well containment device, as shown and described.

DESCRIPTION

FIG. 1 is a first side view of a well containment device showing our new design;

FIG. 2 is a second side view of the well containment device shown in FIG. 1;

FIG. 3 is a third side view of the well containment device shown in FIG. 1;

FIG. 4 is a top plan view of the well containment device shown in FIG. 1;

FIG. 5 is a perspective view of the well containment device shown in FIG. 1;

FIG. 6 is a bottom view of the well containment device shown in FIG. 1; and,

FIG. 7 is a bottom perspective view of the well containment device shown in FIG. 1.
